H. A. CRAWFORD

AEROPLANE SUSPENSION

Filed July 15, 1922

Fig. 2.

Inventor

Henry A. Crawford.

Gordon Stewart

Attorneys

UNITED STATES PATENT OFFICE.

HENRY A. CRAWFORD, OF TULSA, OKLAHOMA.

AEROPLANE SUSPENSION.

Application filed July 15, 1922. Serial No. 575,234.

To all whom it may concern:

Be it known that I, HENRY A. CRAWFORD, a citizen of the United States, residing in Tulsa, in the county of Tulsa and State of Oklahoma, have invented certain new and useful Improvements in Aeroplane Suspensions, for which the following is a full and complete specification, reference being had to the accompanying drawings.

10 My invention consists of means for suspending an aeroplane during its flight either as an amusement device for industrial purposes or for instruction purposes. It has been proposed to suspend an airship during 15 its flight as an amusement device so that passengers may be carried in the machine and given the sensation of actual flight without the attendant risks. In like manner, novices have been instructed in the manipulation of an airplane in flight while the same is constrained to move in a definite limited path. In either case the path of the airship has been a one-way circuit or analogous structure all of which prevent travel in opposite directions over the same course. It 20 is an object of my invention to provide means whereby the airplane may be propelled under its own power and guidance back and forth over a single supporting cable. Other advantages of my device will 25 appear from the following description and accompanying drawings in which latter,

Fig. 1 is a side elevation, and

Fig. 2 is a plane view of the suspending 35 means and associated airplane.

By way of example, I have illustrated an aeroplane 1 which is of conventional type and including propeller 2, landing gear 3, wings 4, rudder 5 and rear elevating means 40 6. The fuselage is open as at 7 to form a compartment in which there is a driver's seat 8 and passenger seats 9. Conventional means are included for producing the power and for accomplishing the customary elevating and guiding movements.

45 A sling, denoted generally by the numeral 10, consists of a rigid forward frame-work having two vertical beams 11 connected at top and bottom by the cross bars 12 and 13 respectively. This frame is substantially the width of the fuselage and somewhat higher than the distance between the bottom of the fuselage and the top of the wings. The fuselage rests upon the bottom cross 55 bars 13 and is held from lateral movement

with respect to the frame by means of the vertical bars, 11, 11, of the latter. This frame is placed in front of the point of attachment of the running gear 3, and the frame is firmly attached to the fuselage.

60 Substantially at the rear of the passenger compartment is a rear frame constructed of side vertical bars 14, lower cross bar 15 and upper cross bar 16. This frame is substantially similar to the forward frame. The fuselage rests upon the cross bar 15 and between the vertical bars 14, 14, which latter are firmly attached to the fuselage.

65 The relative positions of the frames is dependent upon the location of the weights in the airship, it being evident that it is essential to provide "an even keel" for the aeroplane during its suspension. Supporting wires 17 extend upward from the upper cross bars 12 and 14 of the frames and are 70 connected to the ends of the longitudinal strut 18. A wire 19 is connected with the forward part of the strut 18 at one end. A similar wire 20 is connected to the rear portion of the strut. The free ends of the wires 75 19 and 20 are fastened to the ring 21.

The ring 21 forms one part of a swivel, the opposite part of which is the member 22. The eye of the member 22 is held within a U-shaped strap 23 which depends upon the 80 truck 24. The truck 24 is supported on two rollers 25 as indicated.

85 The rollers 25 have recessed outer surfaces adapted to ride upon the cable-way 26. This cable-way is adapted to be stretched taut between two supporting stations 27 and 28. These supporting stations may be built upwardly from the level of the ground a short distance or may be located on opposite sides of a natural valley or run-way.

90 The aeroplane may be loaded with passengers or ballast and driver installed in the appropriate place. Operating under its own motive power and subject, in a limited extent, to the influence of its wings and elevator, the machine is propelled forwardly in the general direction of a cable 26. During this movement the airplane may have a tendency to lift its weight from the forward and rear planes but is not freed therefrom. During the travel of the machine, it may be turned slightly to the right or left. However, this deviation from the straight path is limited by the amount of freedom allowed by the sling 10 and the cable 26. In 100 105 110

this lateral movement the swivel connection 21, 22, permits the greatest turning freedom between the truck 24 and the sling 10.

When the aeroplane has reached the farther limit of the cable 26 the aviator may use the customary rudder 5 to turn the machine around in short radius as permitted by the sling 10 and swivel connection 21, 22. After having been turned around the aeroplane will then travel along the cable in the reverse direction.

In this manner the aeroplane may be made to simulate the conditions and movements of actual flight with the running gear up off the ground and yet suspended from the relatively fixed cable 26. The occupants of the airship thus experience the actual flying conditions and may be trained in the manipulation as a preliminary to actual independent flight.

While I have shown one form which my invention may take, nevertheless many changes may be made in minor details without departing from the spirit of my in-

vention as defined in the accompanying 25 claims.

What I claim is:

1. In combination with an aeroplane, a track, suspending means for the aeroplane including a truck on said track, a sling and 30 a connection between the sling and truck.

2. In combination with an aeroplane, a track, suspending means for the aeroplane including a truck on said track, a sling and 35 a swivel connecting the sling and the truck.

3. In combination, a flexible track mounted between two fixed stations, a truck on said track, a swivel suspended from the truck and an aeroplane sling carried by 40 said swivel.

4. In combination, a track, a truck on said track, a swivel suspended from the truck, and a sling for an aeroplane including a 45 plurality of spaced frames carried by the swivel.

In testimony whereof, I have hereunto affixed my signature.

HENRY A. CRAWFORD.
